UNITED STATES PATENT OFFICE.

DAVID OPPENHEIM, OF NEW YORK, N. Y., ASSIGNOR TO AMERICAN YVETTE COMPANY, INC., OF NEW YORK, N. Y., A CORPORATION OF DELAWARE.

DESIGN FOR A BEAUTY-PARLOR FRONT-ENTRANCE UNIT.

Application filed December 31, 1927. Serial No. 24,717. Term of patent 14 years.

To all whom it may concern:

Be it known that I, DAVID OPPENHEIM, a citizen of the United States, residing in New York, in the county of New York and State of New York, have invented a certain new, original, and ornamental Design for Beauty-

Parlor Front-Entrance Unit, of which the following is a specification, reference being had to the accompanying drawing, showing in Figure 1 an inside perspective view of a beauty parlor front entrance unit of my new design, and in Fig. 2 an outside perspective view thereof.

I claim:

The ornamental design for a beauty parlor front entrance unit as shown and described.

DAVID OPPENHEIM.
